CLAIM

The ornamental design for a syringe connector as shown and described.

DESCRIPTION

1. Syringe connector

1.1: Front view of the syringe connector;

1.2: Back view thereof;

1.3: Right view thereof;

1.4: Left view thereof;

1.5: Top view thereof;

1.6: Bottom view thereof;

1.7: Cross-sectional view along line 1.7-1.7 shown in reproduction 1.5;

1.8: Perspective view thereof; and

1.9: Perspective of a position of use.

This article is a syringe connector, as shown in reproductions; the views including the cross-sectional views (1.7-1.7 line cross-sectional view) specify the portions to be sought as partial design right; Reproduction 1.9 is a perspective view of the article in a position of use. The broken lines

(Continued)

showing of the syringe connector is for the purpose of illustrating portions of the “article” and form no parts of the claimed design.

1 Claim, 9 Drawing Sheets
